UNITED STATES PATENT OFFICE.

PERRY A. SKILES, OF SURREY, NORTH DAKOTA.

ANTISLIPPING ATTACHMENT.

1,242,056.

Specification of Letters Patent.

Patented Oct. 2, 1917.

Application filed December 26, 1916. Serial No. 138,937.

To all whom it may concern:

Be it known that I, PERRY A. SKILES, a citizen of the United States, residing at Surrey, in the county of Ward and State of 5 North Dakota, have invented certain new and useful Improvements in Antislipping Attachments, of which the following is a specification.

This invention relates generally, to boots and shoes, and the invention has more especial reference to an improved anti-slipping attachment for the soles and heels of boots and shoes.

The invention has for its principal object to provide an anti-slipping attachment which can be instantly engaged with the soles and heels of footwear and will enable the wearer to safely walk upon icy or snow covered ground without falling.

20 As an object of equal importance, the invention aims to provide an anti-slipping attachment which can be used in outdoor sports such as baseball, sprinting, jumping and the like, whereby the athlete will be enabled to gain a firm footing when in action.

Still further, the invention aims to provide an anti-slipping device which may be readily detached from a shoe heel or sole, thus permitting ordinary walking shoes to 30 be used.

The improvements in the details and arrangements of parts will be apparent from an inspection of the accompanying drawings, in connection with the specific description hereinafter contained, and wherein the preferred embodiment of the invention is disclosed for the purpose of imparting a full understanding of the invention.

In the drawings:

40 Figure 1 is a side elevation of the improved antislipping attachment as applied to a shoe heel and sole;

Fig. 2 is a bottom plan thereof; and

Fig. 3 is a transverse section taken on the 45 line 3—3 of Fig. 2.

Referring more specifically to the drawings, wherein like reference characters designate corresponding parts in the several views, the present improvements may be 50 stated to embody engaging members 1 and 2, portions of which are provided with hooked members 3, whereby the engaging members 1 and 2 may be securely engaged with the shoe sole. Calks, generally indicated by the numeral 4 are arranged upon

the forward ends of the engaging members 1 and 2 and are formed by bending portions of the said members upwardly and beveling the sides thereof as at 5. A similar set of calks 6 are arranged upon the rear end of 60 the members 1 and 2. In this connection, it is to be noted that the calks 4 and 6 are so arranged upon their respective engaging members 1 and 2 as to be obliquely disposed to the longitudinal axis of the sole. By this 65 means, slipping of the sole, either longitudinally or transversely of the ground will be prevented. Up-struck apertured lugs 8 are formed upon the adjacent sides of the engaging members 1 and 2, preferably intermediate the ends thereof and are adapted to receive therethrough, connecting arms 9, the opposite ends of which are screw threaded as at 10 and have turned into engagement therewith, adjustable locking nuts 11, the 70 said locking nuts being screwed against the lugs 8.

With a view toward providing means whereby the engaging members 1 and 2 may be clamped upon a shoe sole, the adjacent 80 ends of the arms 9 are bent inwardly as at 12 and are pivotally connected to a channeled lever 13, by means of suitable cross pins or rivets 14 which are secured to the opposite walls of said channeled lever. To 85 permit the lower connecting arm 9 to be pivotally connected to the lever 13 slightly beyond the pivotal point of the upper arm 9, an elongated slot 15 is formed in the lever which receives the curved or bent end of 90 the said lower arm. By thus arranging and connecting the arms 9, it is evident that when the lever 13 is in one position, the connecting arms together with the engaging members 1 and 2 will be in extended positions. However, when the lever is swung into the position shown in Fig. 3 a pull will 95 be imparted to each of the connecting arms and they will be caused to assume positions reverse to the positions taken when the 100 members 1 and 2 are in extended positions. Furthermore, by mounting the pivots of the connecting arms out of horizontal alinement upon the channeled lever 13, the said lever will be permitted to be maintained in locked 105 position. In applying the attachment to soles of varying widths, the locking nuts 11 can be adjusted upon the screw threaded extremities 10 of the connecting arms 9, to 110 compensate for the differences in size.

In order to provide anti-slipping means for the shoe heel, engaging members 16 and 17 are provided. The member 16 comprises a substantially rectangular strip of metal having a hooked engaging member 18 formed upon one side thereof and a calk 19 formed upon the remaining side, the said calk being formed by bending a portion of the member 16 at substantially right angles 10 thereto, while the member 17 is formed of a piece of semi-circular metal which has formed upon the peripheral edge thereof, hooked engaging members 20, whereas, the opposite edge thereof is provided with a plurality of calks 21, formed in a manner similar to the calk 19. To secure the engaging members 16 and 17 to the shoe heel, an upwardly bent apertured lug 22 is formed upon the member 17, preferably intermediate 20 the ends thereof, while an opening of suitable size is arranged transversely of the calk 19. Connecting arms 9, similar to those as used in conjunction with the sole attachment are engaged with the apertured 25 lug 22 and the calk 19 and are supplied with a locking nut 11. The adjacent ends of the connecting arms are connected to the locking lever 13, which, when operated in the manner as hereinbefore set forth, will efficiently clamp the said members upon the shoe heel.

When desired, it is evident that the anti-slipping attachments for both the shoe sole and heel may be readily removed therefrom; 35 furthermore, if desired the attachments may be applied to practically any form of shoe and when engaged therewith will offer a positive and durable anti-slipping means.

Still further embodiments than those herein especially defined may be resorted to such as conditions or preference may dictate, as may be in keeping with the hereto appended claims.

I claim:

45 1. An ice creeper including sole pieces, a locking lever, and connecting members having a threaded adjusting means at one end in connection with the sole pieces, the other ends of the connecting members being pivoted to the locking lever and shaped to avoid each other when the ice creeper is locked, the pivot being arranged so that one is lo-

cated above the other to hold the locking lever locked.

2. An ice creeper including sole pieces and 55 a locking lever, and connecting elements between the sole pieces, the connecting elements being pivoted in disalignment with the major axis of the locking lever so that the mounting of one connecting element stands above the other to hold the clamping position of the locking lever.

3. An ice creeper including sole pieces and a locking lever, connecting elements between the sole pieces, the connecting elements being pivoted in disalignment with the major axis of the locking lever so that the mounting of one connecting element stands above the other to hold the clamping position of the locking lever and adjusting means for 65 the connecting elements with respect to the sole pieces.

4. An anti-slipping attachment of the character described, including oppositely disposed engaging members, calks formed 75 integrally with said engaging members, connecting arms adjustably secured to said engaging members, and a locking lever connected to the adjacent ends of said connecting arms for moving the same into and out 80 of clamping engagement.

5. An anti-slipping attachment of the character described, including oppositely disposed engaging members, up-struck calks formed upon said engaging members, connecting arms adjustably secured to said engaging members, and a channeled locking lever having an elongated slot therein, one of said connecting arms being pivotally secured to one end of the locking lever and the 90 other of said connecting arms extending through the elongated slot in the lever and pivotally connected thereto at a point out of horizontal alignment with the pivot of said first connecting arm, whereby the engaging means may be moved to and maintained in clamping position.

In testimony whereof I affix my signature in presence of two witnesses.

PERRY A. SKILES.
